MULTIPLE STAGE THREAD PROCESSING REEL

Lorin A. Corey, Cleveland Heights, Ohio, assignor
to Industrial Rayon Corporation, Cleveland,
Ohio, a corporation of Delaware

Application November 20, 1947, Serial No. 787,245

2 Claims. (Cl. 28—71.7)

1

This invention relates to thread advancing reels upon which a plurality of individual processing steps on a thread or the like can be performed while the thread passes over the reel in a general unbroken helix. More particularly the invention relates to a thread advancing reel whereon steps such as stretching or shrinking can be effected over a prolonged length of a reel having a plurality of sections without appreciable distortion of the thread helix or of the sectionalized bars of the reel.

Advantageously the reel of this invention embodies the principle disclosed in the Knebusch Patent 2,210,914 which is particularly adapted in the manufacture of rayon yarn, thread, etc. by the continuous process where the reel members comprising the reel are arranged to rotate on axes that are eccentric to each other, and where they occupy substantially the same space. Thread or the like is advanced over the periphery of such a reel through the cooperation of a plurality of bar members which form the peripheries of the two reel members.

Generally, a reel having only two reel members has been adapted to the performance of a single processing step. For the performance of a plurality of steps it is advantageous to have a reel capable of accommodating such a plurality of steps. The length of a two-element reel is limited by the relationship between the reel bar members which would interfere if extended too far. For example, with two-member reels where a preparatory processing step is to be performed substantially immediately on the thread prior to a stretching or shrinking operation such a step ordinarily was performed on a separate reel and then the thread was transferred through space to the stretching reel. Where the thread has to travel through the space between two reels prior to a further immediate treatment for instance, in a softening and stretching sequence, the thread would have the tendency to dry and, as a result, some of the effectiveness of the prior treatment would be lost. Also, stretching or shrinking imparts stresses in the bar members of a two-member reel, the stretching of the thread having a tendency to destroy the eccentric relationship between the bars to thus stop thread travel.

Stretching is advantageously effected on such reels by flaring the bar members. Under certain circumstances a two element single stage reel must be flared considerably to provide for a sufficient stretch; however, because of such flaring the threads will sometimes slip, bunch up

2

and thus not advance over the reel. Thus it is desirable to stretch or shrink thread gradually over a reel having a required length.

This invention advantageously provides for a reel having a required length whereon stretching, shrinking, and other processing steps can be performed on the thread in a sequence of operations without distorting either the thread helix, or the reel members comprising the reel. The reel comprises a continuous concentric reel member supported at each end and a plurality of shorter eccentric reel members having substantially full bar support positioned in an end-to-end relation on axes that permit the transfer of the thread helix from the one eccentric member to the next succeeding eccentric member with a minimum of thread helix distortion. The reel processing sections are determined by the eccentric reel members whereon a processing step can be performed and, if necessary, the step can extend over more than one section. For stretching, the bar members can have a gradual flare extending over a plurality of sections if one section length is not sufficient, while for shrinking the reel diameter, of course, can be desirably decreased. Preliminary treatments also can be effected right on the reel.

The manner in which the eccentric reel members are arranged enables an undisturbed transfer of the thread helix from the one eccentric reel member to the next. The method briefly comprises positioning the eccentric reel members in an end-to-end relation so that their axes are circularly arranged about the axis of the concentric reel member or in a manner so that their axes intersect. Further, to effect a smooth transfer of the thread helix from one section or eccentric member to another the thread-bearing members are desirably tapered at their transfer portions, and the tapered ends are made contiguous for a portion of their lengths. The transfer points between each pair of contiguous bar members all lie in substantially the same vertical plane. The thread, as a result, is transferred from the one eccentric member to the other easily and smoothly and without distortion.

The eccentric reel members as well as the one unbroken reel member can have, of course, any desirable shape or contour to effect stretching and shrinking of the thread or either step or any combination of steps that is required to bring out desired final yarn characteristics. Such a multiple stage reel is more thoroughly described in the following specification and the accompanying drawing where;

Figure 1 represents in elevation a multi-stage reel whereon a stretching step can be performed; Figure 2 represents the reel of Figure 1 in cross section; Figure 3 represents in end elevation the reel of Figure 1; Figure 4 is a reel member locking device; Figure 5 represents a modification of the reel in partial cross section and elevation; and, Figure 6 is a further modification of the reel in partial section and elevation.

Referring to the drawing there is shown in Figure 1 a reel that is adapted to perform at least two processing steps on thread or the like passing over its periphery. The reel comprises a plurality of reel members 10, 11, and 12 whose peripheries are formed of pluralities of longitudinally extending bar members 14, 15, 16 respectively. The bar members 15 and 16 are interleaved with the bar members 14 and the total plurality of bar members occupy substantially the same circumferential area.

The sets of bar members 14, 15, 16 cooperate with each other to advance thread lengthwise of the reel in a number of generally helical turns. As shown, the bar members 14 of the reel member 10 are of continuous length throughout the reel while the bar members 15, 16 of the two other reel members 11, 12 are of shorter lengths; however, when combined their lengths substantially equal that of the bar members of the first reel member. Also, as shown, the shape of all of the bar members is such so as to impart a stretch to the thread while it is travelling over the reel periphery. The stretch is imparted to the thread when it is on the flared portion of the reel.

The first part of the reel or that part next to the flange 23 to which the thread is first introduced is shown as being of a uniform diameter throughout its length. It could, of course, be tapered fully or only partially, the taper merging with the tapered forward portion of the reel.

In Figure 2 there is shown the advantageous positioning of the eccentric reel members which sectionalize the reel. The unbroken reel member 10, that is the reel member having a continuous length, is concentrically mounted about a shaft 18. The bar members 14 are supported by radially extending members 19 from a hub member 20 which is positioned about and secured by a set screw 21 to the shaft 18. At the other end the bar members terminate in a flange 23 which is in turn fixed by means of bolts 24 to a flange hub member 25. The hub member 25 is concentrically positioned about a supporting sleeve 27 also having a flange 28. Flange 28 is adapted to be positioned in a spinning machine (not shown) to support the entire reel structure.

Since the shaft 18 is driven, there is positioned about it a stationary sleeve bushing 29 one end of which abuts a collar 22 being part of the shaft. Displacement of the sleeve is prevented by a collar 39 secured to the shaft at the other end. About one end of the sleeve 29 there is positioned the stationary flanged sleeve 27. On the bushing sleeve 29 there are positioned eccentric sleeve members 30, 31 whose axes are offset and askew to the axis of shaft 18 and thus to the axis of the concentric reel member 10. The eccentric sleeves 30, 31 support the sleeve bearings 33, 34 about which rotate the hub members 35, 36 carrying the bar members 15, 16 which form the reel members 11, 12.

The axes of the eccentric sleeves 30, 31 are advantageously arranged so as to cause their intersection. The bar members of the eccentric reel members are also tapered and the tapered

portions are made contiguous. This arrangement permits the transfer of a thread helix from the one section of the reel to the next succeeding section with a minimum of distortion and disturbance.

The eccentric sleeve members are held in the desired position by means of serrations on their ends. The serrations, as shown in Figure 4, also permit a close angular adjustment of the reel members. All members that are mounted about the sleeve bushing 29 are thus locked. Sleeve 31 is locked to the support 27, and sleeve 30 is locked to the end serrated collar 38. A collar 39 having a setscrew 49 which locks it to the shaft 18 keeps all of the aforesaid members in desired positions.

On one end of the shaft 18 there is mounted a driving gear 40. The driving gear 40 desirably contains a slip-clutch 42 which comes into use during periods of unusual torque requirements. The clutch is attached to the shaft by means of a set screw 43 threaded through an extended portion of the clutch to form a hub to bear against the shaft 18.

The reel of Figure 1 is adapted for the performance thereon of at least two processing steps, one step being of a nature which may prepare the thread or the like for a subsequent stretching operation. After the performance of such a processing step the thread is transferred without distortion to the next reel section whereon it is stretched by the flared bar members. As shown, the diameter of the first reel section composed of a section of the bar members 14 and of bar members 16 is the same throughout its length. For a longer stretching operation the taper of the reel can, of course, extend over its entire length.

There is shown in Figure 5 a modification of a reel having a peripheral shape that permits a shrinking of the thread. After a predetermined shrinking has been effected the thread is then permitted to advance in a helix of the same diameter. All of the thread bearing members 14, 15, 16 have complementary configurations making the reel through any section substantially a circle.

After a shrinking process the thread can be again stretched if so desired. A reel for effecting a shrink and then a stretch is shown in the modification of Figure 6. The thread shrinking or relaxing step can be first performed on a reel section of a decreasing diameter; then the thread is transferred to the next succeeding section of the reel having an increasing diameter where stretching will take place. Thus, the shape of the reel can be made to give any desired sequence of processing steps which may involve stretching or shrinking or either step with some other treatment of the thread.

In the drawing there has been shown a reel comprising two sections whereon treatments can be individualized. The advantageous construction and positioning of the eccentric members, however, will permit a reel having a length limited only by physical limitations. A reel having three, four or as many eccentric members as desired can be constructed. The configuration of the bar members may also be in accordance with the final yarn characteristics desired.

I claim:

1. A multiple stage thread processing reel comprising, a reel member having a plurality of longitudinally extending bar members of continuous length, said bar members being of a shape

that is adapted to effect a physical change in thread traveling over them, and at least two reel members in substantially an end-to-end relation each having a plurality of bar members interleaved with said bar members of said first reel member and rotating on axes that are eccentric to the axis of said first mentioned reel member, said eccentric axes being arranged in an end-to-end relation about the axis of the first reel member and at angles so that they intersect, the bar members of said two reel members in their combined length being substantially equal to the length of the bar members of said first reel member and their shape conforming to the shape of the bar members of said first mentioned reel member.

2. A multiple stage thread processing reel comprising, a reel member of a varying diameter having a plurality of longitudinally extending bar members of continuous length, said bar members being of a shape that is adapted to effect a physical change in thread traveling over them, at least two end-to-end eccentrically positioned reel members also of varying diameters generally conforming to the diameters of the longitudinally extending reel member, each of said eccentrical-

ly positioned reel members having a periphery of a plurality of bar members, said bar members being interleaved with the bar members of said first reel member, said eccentric reel members being mounted for rotation on axes that are offset and askew to the axis of said first reel member, the said offset and askew axes being arranged about the axis of the first reel member in an end-to-end relation and at angles so as to intersect, and the end-to-end portions of the bar members of said eccentric reel members being contiguous.
